United States Patent Office

Des. 182,472

Patented Apr. 8, 1958

182,472

CAN OPENER

Ralph C. Lynch, Milliken, Colo.

Application May 27, 1957, Serial No. 46,370

Term of patent 14 years

(Cl. D44—29)

Fig. 1 is a front view of a can opener, showing my new design;

Fig. 2 is a side view thereof; and

Fig. 3 is a bottom view thereof.

I claim:

The ornamental design for a can opener, as shown.
